The ornamental design for a combined foldable and portable sink table, as shown and described.

DESCRIPTION

FIG. 1 is a perspective view taken from the top, front and left side of a combined foldable and portable sink table showing my new design;

FIG. 2 is a perspective view taken from the top, front and left side showing the unit in a partially folded position;

FIG. 3 is a perspective view showing the unit in its closed position;

FIG. 4 is a top plan view of FIG. 1;

FIG. 5 is a front elevational view of FIG. 1;

FIG. 6 is a rear elevational view of FIG. 1;

FIG. 7 is a bottom plan view of FIG. 1; and,

FIG. 8 is a left side elevational view of FIG. 1, the right side being a mirror image of the left side.

FIG. 1

FIG. 2

FIG. 3

FIG. 4

FIG. 5

FIG. 6

FIG. 7

FIG. 8
